UNITED STATES PATENT OFFICE.

PILADE BARDUCCI, OF MILAN, ITALY.

DRYING PLANT.

Application filed June 8, 1923. Serial No. 644,228.

To all whom it may concern:

Be it known that I, PILADE BARDUCCI, a subject of the King of Italy, residing at Milan, Italy, have invented a new and useful

5 Improvement in Drying Plants; and I do hereby declare the following to be a full, clear, and exact description of the same.

The present invention relates to drying plants and has for its object a drying room 10 which comprises means travelling along the same and producing a vertical air current above them and other currents at an angle to the first one which are directed along the path of said means, stationary means being 15 provided at one end of the room which produce air currents meeting those produced by said travelling means and combining therewith.

According to this invention an even operation 20 is obtained of the plants comprising travelling ventilating means, because the air circulation produced by the stationary means acts to control the direction and intensity of the streams produced in the room.

25 Further said end stationary ventilating means act to exhaust a portion of the air from the room and introduce into the same fresh air, and they may also be provided with means for heating or cooling or, generally speaking, treating the air flowing through them.

The annexed drawing shows diagrammatically the operation of the plant in different conditions of operation and the path 35 of the ventilating streams which may be obtained according to this invention. In said drawing: Figure 1 is a longitudinal vertical section of a drying room with the reciprocating ventilating apparatus in an intermediate position between the ends of the room; Figure 2 is a similar section with said travelling ventilating apparatus at the end of its stroke removed from the stationary ventilating means; Figures 3 and 4 are views 45 similar to Figures 1 and 2, the direction of the air currents being assumed to be reversed; Figure 5 is a fragmentary section of the room to an enlarged scale showing in detail the construction of the end stationary ventilating apparatus and Fig. 6 is a sectional view showing the travelling apparatus.

50 According to this invention in the ventilating or drying room 14 is located a ventilating apparatus which is adapted to reciprocate through the room, which is assumed

to have an elongated shape, and the operation of said reciprocating ventilating means is combined with stationary ventilating means located at one of the ends of the room 60 14 as hereinafter fully described.

The reciprocating apparatus, (see Figure 5) comprises a casing 1 having a top mouth 2 and a front mouth 3 and provided with means for its reciprocation as wheels 5 running on rails 13 and an electromotor 6 whose circuit is fed by a trolley 7 and a line 8 suspended in the room.

Said casing 1 encloses an air propeller 9 driven by an electromotor 10 and a partition 11 operated by a lever 12 arranged outside of the casing, for controlling the communication of the top mouth 2 with the front mouth 3; by this arrangement said mouth 2 may be put in communication with the 75 mouth 3 through a more or less large or restricted passage to adjust the flow of air through the device.

It is to be understood that this embodiment of ventilating apparatus is shown and 80 described merely for purpose of illustration but the present invention is not restricted to the particular construction described and illustrated, it being only limited as required by the appended claims.

It is also to be held in mind that many features are not claimed per se in this application they being described and claimed in my U. S. Patent No. 1,381,054 and in my copending application Ser. No. 538,037, to 90 which attention is called.

At one end of the room is provided a casing 15 which has a top mouth 16 and a bottom mouth 17 and comprises a reversible air propeller 18 (see Figure 5). To said casing 95 lead ducts 19 and 20 each of which opens in register with one of said mouths 16 and 17 and said ducts are provided with valves 21—22 for controlling the flow of air through each of them and the casing mouth 100 in front of the same.

Finally in said casing 15 are provided, if desired, means for heating, cooling or treating the air, which are shown conventionally as a coil 23.

105 The air propellers 9 and 18 are intended to cooperate with each other as hereinafter fully described, and the propeller 9 acts to put the air in circulation within the room, while the propeller 18 produces air currents 110 in the room which cooperate with those produced by the travelling one to improve the

2
ventilation and produce well defined air streams through the room.

Further the said propeller 18 produces a circulation of air through the chamber or casing 15 and causes the exhaust to the outside of a portion of the air flowing through said casing and a supply of fresh air from the outside into the casing and room.

By adjusting the delivery of each of the 10 propellers 9 and 18 with respect to the other one, the amount of air propelled by the propeller 18 may be made equal to or less or larger than that moved by the propeller 9 through the mouths 2 and 3 cooperating 15 with the mouths 16 and 17 of the casing 15, for the purpose of modifying the rate of circulation of the air within the room.

In the several figures the material to be dried is assumed to be located in the space 20 enclosed between the horizontal dotted lines above the travelling casing 1.

As shown by the Figures 1-4, the room 14 is provided at one of its ends with one or more casings 15 and the front wall of 25 the ventilating carriage 1 has its mouth 3 opening in front of or opposite to the said casing or casings.

When the propellers 9 and 18 are operated and the carriage is reciprocating 30 throughout the room, air currents are produced in the room which follow substantially the path shown by the arrows in Figures 1 to 4, when the operation of the propellers 9 and 18 are so related with 35 regard to each other as to produce air currents directed in the same circuitous direction.

Of course different air streams may be obtained by giving opposed directions to the 40 air streams issuing from the mouths of the casing and carriage.

For preventing uncontrolled air streams or eddies from taking place within the room, through the inlet mouth 16 of the casing 15 45 must be introduced a volume of air substantially equal to that of the air propelled by the propeller 9 of the carriage, and the operation of the propellers must be adjusted to comply with this requirement as well as 50 with the above stated one with respect of the direction of air currents.

The ventilation in the room is therefore produced by a single current flowing vertically above the space occupied at any time 55 by the ventilating carriage 1.

The ventilation of the material is made even, because the air current acting on it has at any time a constant value. For reversing the ventilation it suffices to reverse 60 at predetermined intervals of time the operation of the propellers 9 and 18 so as to reverse the direction of the air flow through the mouths of the casing 15, and then the air circulation shown by Figures 3-4 is obtained.

By the arrangement according to this invention a large volume of air is circulated through the casing 15 and the operation of the propelling means of this casing may be caused to cooperate in such a manner with 70 that of the carriage as to make very even the conditions as to dryness and temperature of the air streams passing through the material, while doing away with any cumbersome apparatus located within the room and 75 intended to heat and change the air.

Further very different drying or ventilating methods can be carried into practice by causing the space occupied by the material to be passed through by a vertical current above the ventilating carriage, and by 80 other currents opposite to the first one which may be more or less strong; further in the drying room may be produced a single vertical current above the carriage as required 85 for obtaining alternate ventilation of the material in comparatively short rooms.

Finally by the means arranged in the casing 15 the same ambient air of the room may be circulated or an amount of fresh air 90 may be introduced into the room and a portion of the air driven out from the room may be exhausted.

It is to be understood that the constructions illustrated are given merely by way 95 of example and that many changes may be made therein, and still be clearly within the spirit of this invention which is defined by the appended claims.

What I claim as my invention and desire 100 to secure by United States Letters Patent is:—

1. In a plant for drying materials, a room 105 intended to contain the material to be dried, means reciprocating in said room and adapted to produce vertical air currents and air streams directed along the path of said means, and means at one end of said room producing therein air currents directed towards and from said reciprocating means, respectively.

2. In a plant for drying materials, a room 110 intended to contain the material to be dried, means reciprocating in said room and adapted to produce vertical air currents and air streams directed along the path of said means, said means comprising suction and exhaust mouths, and means at one end of said room producing therein air currents directed towards said suction mouth and air currents coming from said exhaust mouth.

3. In a plant for drying materials, a room 115 intended to contain the material to be dried, means reciprocating in said room and adapted to produce vertical air currents and air streams directed along the path of said means, said means comprising suction and exhaust mouths, and means at one end of said room producing therein air currents directed against said exhaust mouth and air 120 currents coming from said suction mouth.

130

currents departing from said suction mouth.

4. In a plant for drying materials, a room intended to contain the material to be dried, means reciprocating in said room and adapted to produce vertical air currents and air streams directed along the path of said means, a casing having mouths opening in said room, air propelling means in said casing intermediate said mouths, a port for discharging an amount of air from said casing, a port for supplying an amount of air into said casing, and means for adjusting the air flow through said ports.
5. In a plant for drying materials, a room intended to contain the material to be dried, means reciprocating in said room and adapted to produce vertical air currents and air streams directed along the path of said means, a casing having mouths opening in said room, air propelling means in said casing intermediate said mouths, a port for discharging an amount of air from said casing, a port for admitting an amount of air into said casing, means for adjusting the flow of air through said ports, and heat exchanging means in said casing, these means being intermediate said exhaust and inlet ports of said casing.
- 20 5. In a plant for drying materials, a room intended to contain the material to be dried, means reciprocating in said room and adapted to produce vertical air currents and air streams directed along the path of said means, a casing having mouths opening in said room, air propelling means in said casing intermediate said mouths, a port for discharging an amount of air from said

casing, a port for admitting an amount of air into said casing, means for adjusting the 25 air flow through said ports and heat exchanging means in said casing.

6. In a plant for drying materials, a room intended to contain the material to be dried, means reciprocating in said room and adapted 30 to produce vertical air currents and air streams directed along the path of said means, a casing having mouths opening in said room, air propelling means in said casing intermediate said mouths, a port for discharging an amount of air from said casing, a port for admitting an amount of air into said casing, means for adjusting the flow of air through said ports, and heat exchanging means in said casing, these means being intermediate 35 said exhaust and inlet ports of said casing.

In testimony whereof I have signed my name to this specification.

PILADE BARDUCCI.
